UNITED STATES PATENT OFFICE.

GEORGE L. MORRISON, OF HUDSON, MICHIGAN, ASSIGNOR TO THE MORRISON BOX COMPANY, OF TOLEDO, OHIO, A CORPORATION OF OHIO.

PAPER-BOARD BOX.

1,090,559.

Specification of Letters Patent.

Patented Mar. 17, 1914.

Application filed February 1, 1913. Serial No. 745,607.

To all whom it may concern:

Be it known that I, GEORGE L. MORRISON, a citizen of the United States, and a resident of Hudson, in the county of Lenawee and State of Michigan, have invented a certain new and useful Paper-Board Box; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to single-piece collapsible paper-board boxes, and has for its object to improve upon the construction of boxes of this character whereby to quite securely interengage the sides of the bottom and cover sections of the box at the rear corners thereof when in closed set-up form to strengthen the box at such points and to resist an opening of the sections, thus enhancing the practicability and commercial value of boxes of this nature.

The invention is fully described in the following specification, and while, in its broader aspect, it is capable of embodiment in numerous forms, a preferred embodiment thereof is illustrated in the accompanying drawings, in which,—

Figure 1 is a view of the box blank, Fig. 2 is a perspective view of the box in folded form with the sections thereof in partly open position. Fig. 3 is a rear perspective view of the box with the rear end of one side of the cover partly sprung outward from its interengaged position with the adjacent corner portion of the box. Fig. 4 is a front perspective view of the box in closed position with a part broken away, and Fig. 5 is a plan view of the box collapsed in condition for storage or shipment.

The blank from which the box embodying the invention is formed, comprises the bottom or body section A and the top or cover section B, which are hinged at their adjacent edges to a back or center connecting strip C along the lines c, c. The body section A is scored adjacent to its side and front edges by lines a and a', respectively, each of which is parallel to the adjacent edge and a distance therefrom equal to the

height of the box desired, to form the sides 1, 1 and the front 2 of the bottom section. 55 The front corners 3 of the body section A are separated from the ends of the front 2 by slits 4, and form extensions of the respective sides 1. The rear ends of the sides 1 of the body sections are also provided 60 with tongue extensions 5, which extend substantially half-way across the width of the connecting strip C and are separated therefrom by slits 6, which slits are in longitudinal register with the side scorings a and b. 65

The cover section B is provided adjacent to its side and front edges in parallel relation thereto with scorings b and b', respectively, which are preferably spaced from the respective edges a distance equal to the 70 height of the box desired and form the sides 7, 7 and the front 8. The front corners of this section are provided with tongues 9, which form extensions of the front side 8, being hingedly attached thereto along extensions of the scorings b, b' and being separated from the sides 7, 7 by slits 10. The inner or rear end of each side 7 is provided with a tongue or extension 11, which projects toward the adjacent tongue 5 of the 80 body section A and is separated from the end of the part C by a space 12. The tongues 11 are of less width than the sides 7 due to the cutting away of the blank, as at 12, for the purpose hereinafter described. 85

To form the blank into a box, the sides 1 and front 2 of the section A and the sides 7 and front 8 of the section B are turned up at right angles to the respective sections along the respective scorings or fold lines 90 a, a' and b, b' and secured in such position by the lapping of the tongues 3 either in front or rear of the adjacent ends of the front 2 of the body section and by the lapping of the tongues 9 preferably at the outer 95 side of the adjacent sides 7, 7 of the cover section and securing the tongues to parts which they respectively lap by staples 13, or in any other suitable manner. The tongues 5 at the rear ends of the sides 1, 1 10 of the body section are folded inwardly against the inner side of the respective ends of the rear wall or connecting part C of the sections to coöperate therewith to form an outwardly opening pocket 14 at each rear 101 corner of the box, into which the flaps or

tongues 11 of the cover sections are intended to be inserted when the cover section is closed down over the bottom section, as indicated in Figs. 3 and 4. The tongues 5 are secured to the rear wall C by staples 15, which are disposed adjacent to the top edge of such wall in register with the cut-away portions 12 of the tongues 11, whereby the tongues may be inserted into the pockets 10 14 over the staples, as indicated. To insert the tongues 11 into the rear corner pockets 14 of the box, it is necessary to spring the rear ends of the cover sides 7 outwardly for such purpose, as indicated in Fig. 3.

15 It is found in practice that the provision of the tongue-and-socket feature at the rear corners of the box materially strengthens such corners against collapsing stresses, and tends to resist a relative opening of the bottom and cover sections so that it is not necessary ordinarily to wrap a securing string around the box to retain the sections in closed relation. The insertion of the tongues 20 11 into the pockets 14 also serves to retain 25 the rear ends of the cover sides in contact with the sides of the bottom section.

In order to render the box collapsible in its folded or set-up state, the sides 1 of the body section are diagonally scored on their 30 inner sides, as at 16, to permit an inward collapsing of the front and rear sides of the bottom section thereover, while the cover section preferably has its front side 8 diagonally scored, as at 17, to permit an outward 35 collapsing of such side and an inward folding of the sides 7, 7 against the major portion of the cover section, as indicated in Fig. 5. The cover section is then folded over the bottom section along the upper 40 score line c to place the box in compact form for storing or shipping.

I wish it understood that my invention is not limited to any specific construction, arrangement or manner of folding of the 45 parts of the box embodying the invention except in so far as such limitations are specified in the claims.

Having thus described my invention, what I claim as new, and desire to secure by Letters Patent, is,—

50 1. A box having hingedly connected bottom and cover sections each provided with three sides and a common fourth side, the bottom section being provided at its rear 55 corners with pockets and the cover section being provided at its rear corners with tongues adapted to fit into said pockets when

the sections are in closed relation, substantially as described.

2. A box having a common rear wall and bottom and cover sections hingedly connected thereto with the opposite side walls of the bottom section provided at their rear ends with tongues which lap and are secured to the inner side of the common rear wall of the sections and coöperate therewith to form outwardly opening rear corner pockets, and with the sides of the cover section provided at their rear ends with rearwardly projecting tongues adapted to be inserted into said pockets at an angle to the box sides when the box sections are in closed relation.

3. A single-piece paper-board box having hingedly connected bottom and cover sections each provided with a front and opposite side walls and with a common rear wall, with the bottom section provided at its rear corners with pockets which open outwardly in the plane of the rear wall and with the rear ends of the cover section side walls provided with tongues adapted to be turned at right angles to said side walls and to project into the registering corner pockets of the bottom section when the two sections are in closed relation.

4. A single-piece box blank having bottom and cover sections each provided with scorings adjacent to its outer edges to form front and side walls and each being slotted adjacent to its outer corner to provide tongue extensions from the ends of certain of said walls forlapping and securing to the end portions of the other walls when the blank is folded to form a box, a center section hingedly connected to each of the adjacent edges of the bottom and cover sections and adapted to form a common rear wall therefor, the inner or rear ends of the side walls of the respective sections each having a tongue projecting therefrom transversely of said center section and separated therefrom, with the tongues of the cover section of less depth and separated a greater extent from the center section than the tongues of the bottom section, substantially as and for the purpose described.

In testimony whereof, I have hereunto signed my name to this specification in the presence of two subscribing witnesses.

GEORGE L. MORRISON.
